UNITED STATES PATENT OFFICE.

WILHELM HOPF, OF KIEL, GERMANY, ASSIGNOR TO FRIED. KRUPP AKTIENGESELLSCHAFT GERMANIAWERFT, OF KIEL-GAARDEN, GERMANY.

WATER-TUBE BOILER.

1,129,803.

Specification of Letters Patent. Patented Feb. 23, 1915.

Application filed May 10, 1911. Serial No. 626,184.

To all whom it may concern:

Be it known that I, WILHELM HOPF, a citizen of the German Empire, residing at Kiel, Germany, have invented certain new and useful Improvements in Water-Tube Boilers, of which the following is a specification.

This invention relates to a water tube boiler with narrow tubes, having at least one upper water drum, two lower water drums and nests of narrow tubes connecting the upper and lower drums, together with two superheaters, said superheaters are arranged outside of the tube nests that close it from the fire.

This invention relates more particularly to the arrangement of the guiding walls for the heating gases, whereby it has been made possible in coöperation with dampers in a boiler of very simple construction either to lead the heating gases by the superheaters of higher temperature or by entirely excluding the superheaters.

Two constructional forms of a boiler according to this invention are shown on the accompanying drawings at Figures 1 and 2, both of which are vertical transverse sections of so much of the same as will be necessary for the purposes of this specification.

The boiler shown in Fig. 1 consists of an upper water drum A, which communicates by two nests of tubes B with two lower water drums C. Between the nests of tubes is located the furnace D. Outside the nests of tubes B and on each side of the boiler is arranged a superheater E, in front of each of which is placed a damper G, which can be moved into a lower and an upper extreme position. Into the nests of tubes B are

built guide walls for the heating gases, which guide walls are made of fireproof material (such as fire clay or the like) and consist of a longer portion F running longitudinally of the nest of tubes, and a shorter portion F¹ lying at right angles to the group. The portion F of the guide walls might also be a closed wall formed by a row of tubes, as is well known *per se*. The walls F¹ and the dampers G are so arranged with relation to each other, that the dampers G when in the lower position, form a continuation of the guide walls F¹ for the heating gases.

When the dampers G are in the lower extreme position shown in the drawing, the

heating gases sweep first through only the small number of inner rows of tubes shut off by the guide walls F and over the short upper parts of the remaining rows of tubes. They then pass through the superheaters 60 at still very high temperatures and after that sweep through the remaining rows of tubes in the group of tubes B. When the dampers G are in the upper position however, the superheaters are shut off by the 65 dampers and the fire gases pass through the nests of tubes B only.

The difference between the boiler shown in Fig. 2 and the one above described is that two additional water drums A³ are 70 provided. These are likewise connected to the lower water drums C² by nests of tubes B² into which the guide walls F² for the heating gases are built. The arrangement of the guide walls F³ F⁴ for the heating gases 75 in the central nests of tubes B³ and of the dampers G², accords with that of the boiler shown in Fig. 1. A² is the upper central drum and D² is the furnace.

When the dampers G² are in the lower 80 extreme position shown in the drawing, the heating gases sweep first through the small number of rows of the nests of tubes B³ lying inside the walls F⁴ and over the short parts of the tubes lying above the walls F³, 85 pass next in a very highly heated state, into the superheaters E², then sweep through the remainder of the nests of tubes B³ and after that pursue their way guided by the guide walls F², through the nests B², to which 90 they give up the rest of the heat which they contain. When the dampers G are in their upper extreme position, the superheaters are shut off, and the heating gases pass through the nests of tubes B³ B² only. The lower 95 part F⁴ of the guide walls for the heating gases might also be formed by a tube wall. The guide walls F² in the outer nests of tubes B² might be omitted. In such case the uptake for the heating gases should be 100 preferably placed at the upper end of the nests B² between the upper water drum A³ and the superheater.

Having thus described the invention, what is claimed and desired to be secured by Letters Patent is:

1. In a water tube boiler, having a plurality of water drums symmetrically deposited in two layers, an even number below and an odd number above, and a furnace be-

tween the drums in the lower layer, the combination with nests of narrow tubes connecting the upper drums to the lower drums, each nest comprising a plurality of parallel running tubes; of a superheater situated symmetrically on each side of the central upper drum placed so as not to come in contact with said narrow tube nests; guide walls for the heating gases built into the 10 central pair of tube nests, the lower part of said walls running parallel to said narrow tubes and dividing them into two unequal bunches, with the fewest tubes innermost; the upper parts of said guide walls diverging 15 approximately at right angles across said tube nests; dampers constructed to have two extreme positions, forming continuations to said diverging guide walls when in the lower position, and standing at approximately right angles to said guide walls when in the upper position, said guide walls and dampers, when in their lower position compelling the gases from the furnace to sweep through the smaller bunch of narrow 20 tubes, between the guide walls, then across through the superheaters, finally to sweep through the parts of the nests outside of the guide walls; and with the dampers in their upper position compelling the gases to 25 pass inside and outside said guide walls but without passing through the superheaters.

2. In a water tube boiler a central upper water drum, two upper and two lower side

water drums symmetrically disposed relative to said central drum; one pair of nests 35 of narrow tubes for each of said lower drums connecting them with said central drum, and an upper side drum respectively; a pair of guide walls running upward from each of said lower drums parallel to said tube nests 40 respectively, and dividing the tubes in each of said nests into a large and a small bunch, the larger bunches in each pair of nests lying adjacent each other; a third guide wall suspended from the roof of the boiler 45 between said central drum and each of the upper side drums; superheaters situated symmetrically on both sides of said central drum and between said third guide walls and a damper for each superheater situated 50 to form a continuation of the respective inner guide wall in order to direct the gases through the superheater, said damper being disconnected from said inner guide walls when the superheaters are not in use; whereby the combustion gases are compelled to 55 approach the inner tubes in one direction and to leave the outer tubes in the opposite direction.

In testimony whereof I have affixed my 60 signature in presence of two witnesses.

WILHELM HOPF.
